UNITED STATES PATENT OFFICE.

SINGLETON YOUNG SWEENEY, OF ROANOKE, VIRGINIA.

AERIAL RAILWAY.

No. 889,642.

Specification of Letters Patent.

Patented June 2, 1908.

Application filed May 28, 1907. Serial No. 376,145.

To all whom it may concern:

Be it known that I, SINGLETON YOUNG SWEENEY, a citizen of the United States, residing at Roanoke, in the county of Roanoke 5 and State of Virginia, have invented certain new and useful Improvements in Aerial Railways, of which the following is a specification.

My invention relates to aerial railways and consists in constructing an apparatus of this 10 character in such manner that carriers can pass readily from rigid rails to cables which, with the rails, constitute the track apparatus, as fully set forth hereinafter and as illustrated in the accompanying drawing, in 15 which—

Figure 1 is a plan of sufficient of an aerial railway provided with rigid and cable track sections and of carriers adapted thereto to illustrate my invention; Fig. 2 is an end view 20 of a car, and Figs. 3, 4 and 5 are sectional views illustrating different ways in which the wheels of the carriers may be constructed in connection with my invention.

In the construction shown in the drawing, 25 the rail portion of the track consists of parallel rigid rails A, A supported in any suitable manner, and parallel flexible supports or cables B, B which, as shown, are inside the rails A; that is, on different vertical planes, 30 although they may be outside the latter, if desired, or there may be a single track consisting of a line of single rigid rails A and a single cable B.

To the track portion of the apparatus is 35 adapted the carrier C which may have but a single wheel, if adapted to a single track road, or preferably, as shown, is adapted to a double track road, using either two pairs of wheels, as shown, or a single pair, if desired. 40 In any case each wheel D is provided with a tread a adapted to the rigid track A and at one side of the said tread is an annular groove b, so positioned that it will receive the cable B when the tread a passes from the rigid track 45 portion. By this construction the carriers are adapted to travel with equal facility upon both the rigid and the cable portions of the elevated tracks and are effectually supported thereon, being propelled through the medium 50 of a draft cable X, or in any suitable manner.

In the drawings, Figs. 1, 2 and 3, I have shown the wheels with annular grooves inside the treads a and in Fig. 4 I have shown the same disposition, except the groove is

outside the flange c. In Fig. 5 I have shown 55 the grooved portion outside the tread.

The carriers are propelled by a propelling cable X, each carrier connected to said cable by a suitable grip or clutch, not shown.

Without limiting myself to the special 60 construction and arrangement of parts shown, I claim as my invention:

1. In an aerial railroad, the combination of a track of partly rigid rails and partly cables, and carriers adapted thereto and 65 provided with wheels each having a tread adapted to the rail and an annular groove adapted to the cable part of the track.

2. The combination in an aerial railway of a track consisting of parallel rigid rails 70 and parallel cables and carriers having wheels, each wheel adapted to both the rigid and cable portions of the track.

3. The combination in an aerial railway of a track consisting of parallel rigid rails 75 and parallel cables, the latter on different vertical planes from the rails, and carriers having axles, each axle carrying a pair of wheels, and each wheel having an annular tread adapted to the rail portion of the 80 track and at the side thereof an annular groove adapted to the cable portion of the track.

4. In an elevated system, the combination with a rail-way of a cable-way having 85 its ends fixed, said rail and cable-way forming a continuous track for a car, and being located in different horizontal planes at their junction.

5. In an elevated system, the combination of rail-way and a cable-way joined to form a continuous track for a car, said rail-way and cable-way having a common support at their junction and being located in 90 different horizontal planes. 95

6. In an elevated system, the combination of a rail-way and a cable-way joined to form a continuous track for a car, said rail and cable-ways at their junction having a common support and being located in different vertical planes. 100

7. In an elevated system for suspended carriers or cars, the combination of a rail-way and a cable-way joined to form a continuous track for a car, said rail-way and cable-way at their junction being located in different horizontal planes. 105

8. In an elevated system for suspended

carriers or cars, the combination of a rail-way and a cable-way joined to form a continuous track for a car, said rail-way and cable-way at their junction being located in different vertical planes.

9. In an elevated system for suspended carriers or cars, the combination of a rail-way and a cable-way joined to form a continuous track for a car, said rail-way and cable-way at their junction being located in different horizontal and vertical planes.

10. In an elevated system for suspended carriers or cars, the combination of a rail-way and a cable-way joined to form a continuous track for a car, said rail-way and cable-way at their junction being located in different horizontal planes, and a car adapted to travel upon either the rail or cable-way.

11. In an elevated system for suspended

carriers or cars, the combination of a rail-way and a cable-way joined to form a continuous track for a car, said rail-way and cable-way at their junction being located in different vertical planes, and a car adapted to travel upon either the rail or cable-way.

12. In an elevated system for suspended carriers or cars, the combination of a rail-way and a cable-way joined to form a continuous track for a car, said rail-way and cable-way at their junction being located in different horizontal and vertical planes, and a car adapted to travel upon either the rail or cable-way.

In testimony whereof I affix my signature in presence of two witnesses.

SINGLETON YOUNG SWEENEY.
